UNITED STATES PATENT OFFICE.

GUSTAVE PERRON, OF PARIS, FRANCE.

SPOOL HOLDER FOR BRAIDING-MACHINE SPINDLES.

Original application filed June 30, 1922, Serial No. 571,922, and in France July 5, 1921. Divided and this application filed November 24, 1923. Serial No. 676,813.

The present invention relates to a spool holder for braiding machine spindle in which the spool is laid horizontally, this application being a division of my application 5 Serial No. 571,922, filed June 30, 1922.

Said spool holder is essentially characterized by the fact that the bracket acts as a support for two levers capable of oscillating in a vertical plane, one of said levers 10 acting as tension lever for the thread and the other as locking pawl for the spool, said levers being such that, after the locking pawl of the spool has left a certain amount 15 or length of thread to unwind, the tension lever, under the pull of the thread, swings and comes nearer the locking pawl and an arm of the bracket on which is formed the starting eyelet of the thread, so that the eyelets formed on the two levers above referred to and the eyelet on the bracket are substantially in straight line.

The tension lever is submitted to the action of an adjustable tension spring, but it is arranged in such a manner that the said 25 spring acts on said lever through a lever arm which decreases as the tension of the spring increases.

The locking pawl of the spool is formed by a lever of the first kind always tending 30 to be held in the locking position under the action of tension exerted on the thread by the tension lever; through its lower arm, it acts on lateral teeth of the spool flange; through its upper arm, it receives from the 35 tension lever the necessary impulse for unlocking, at a point as far as possible from its pivot, so that the said impulse requires a strain as weak as possible.

On the annexed drawing given by way of 40 example:

Figs. 1 and 2 show in face elevation the spool holder object of the present invention;

Fig. 3 is a side elevation;

Fig. 4 shows the locking pawl in perspective.

The spool holder comprises a bracket 23 secured on the shuttle 12 of the spindle foot 11 by means of two screws which eventually 50 are also holding a guide plate 13 when the spindle comprises a part of this kind.

On the said bracket, is secured a pin 24 on which is placed the spool 28. This spool

is held in place by a spring blade 25 which can swing at 26 in a vertical plane at right angles to the spindle 24. The said spring rests on a shoulder 27 provided at the end of the pin 24 so that the spool 28 is held between the bracket 23 and the spring 25 without however the latter being able to rub 60 against the disc 29 of the spool.

To the bracket 23, is pivoted at 30 a stretching or tension lever 31 the shape of which can vary according to the kind of raw material to be used, and which acts on 65 the thread owing to the helical spring 32 secured at 33 to said lever and at 34 to the bracket.

The mounting of lever 31, spring 32 and pivot 33 is such that, when the spring is not 70 stretched, the line 30, 33 is substantially at right angles to the axis of spring 32 so that as the lever 31 swings and comes nearer the center of the spindle, the acting line of the spring 32 comes nearer the pivot 30 75 (Figs. 1 and 2).

The hooking to the bracket 23 of the end 34 of the said spring could be effected at one of the different orifices 34 provided on the projection 35 of the bracket 23. The lever 80 31 is guided in its movements by the walls of a groove 23' of the bracket 23.

A locking pawl 36 shown in perspective in Fig. 4 is also pivoted at 37 to the bracket 23.

This pawl is controlled by the action of a spring 38 secured, on the one hand, to the pawl at 39, and hooked, on the other hand, into one of the orifices 40 of the projection 41 of the bracket 23.

This locking pawl has an extension or tail 42 which engages in notches 43 provided in the flange 44 of the spool 28 which is a metal spool.

The locking pawl 36 forms a lever of the 95 first kind the pivot of which is formed by the spindle 37. The amount of angular movement which is necessary for producing the unlocking of the spool being very reduced, owing to the fact that the notches 100 43 provided in the flange 44 of the spool are very shallow, it is possible to locate the impulse of the tension lever 31 at a point very near to the upper end of the pawl 36. By these means the necessary driving action 105 happens to be very weak and does not tend

to set on the thread an excessive strain when the spool is to be unlocked.

The bracket 23, the tension lever 31 and the locking pawl 36 are provided respectively with an eyelet 45, 46 and 47 for the passage of the thread coming from the spool, said eyelets being such that, at the moment the spool is unlocked, when the parts are in the position shown in Fig. 2, 10 said eyelets are substantially in line one with another.

The working of the device is as follows:

The thread coming from the spool 28 passes successively through the eyelets 47, 15 46 and 45, from there, it leads to the braiding point. The said eyelets could be moreover split eyelets facilitating the threading of the ends of the threads. The thread passing then through the locking part of the 20 spool and being submitted to the action of the tension lever 31, exerts on this part, which, in the case under consideration, is the locking pawl 36, a pull such that, except when the said lever 31 acts upon the pawl 25 to swing same, it tends to hold the part 42 of said pawl at the bottom of a notch 43 of the spool, without any jar or vibration being able to produce an undesired unlocking of the spool. The spring 38 is a very light 30 spring which is only designed for acting as safety spring preventing the pawl 36 from falling on the spool 28, when the thread breaks.

When the thread is pulled, the lever 31 is 35 brought nearer the centre of the spindle and in coming into contact with the locking pawl 36, acts on the latter (Fig. 2), swings it, which results in disengaging the part 42 from the notches 43 of the disc or flange 44 40 of the spool and in releasing the latter. The thread is then unwound but it is at once stretched again by the lever 31 which, under the action of its spring 32, is moved away from the pawl 36. The latter, under 45 the pulling action exerted on the lever 31 by the spring 32, resumes its position and locks the spool. After which the withdrawal of the thread continues, the tension being exercised by the lever 31; the said 50 tension could be regulated by modifying the spring 32.

If the thread breaks, the spring 32 pulls 55 violently back the lever 31 which can, by coming in contact with a suitable metallic part, close the energizing circuit of an electrically operated automatic throwing out of gear mechanism.

Independently of the fact that it acts reliably at high speeds, the tension device object of the present invention has the advantage that it secures a practically constant tension of the thread, because, as the lever 31 comes nearer the pawl 36, that is to say as the spring 32 becomes stretched more, 60 the line of action of said spring comes nearer

the centre of rotation of said lever 31 so that the increase of tension of the spring is balanced in its effects by the shortening of the lever arm through which said spring acts. 70

On the other hand, as, when the lever 31 acts on the locking pawl 36 for releasing the spool 28, the eyelets 45, 46, 47 are substantially in straight line and as at the same time, the thread has no sharp bend between the spool and the braiding point, the friction of said thread becomes precisely lessened at the moment when the swinging of 36 requires a very slight strain, which ensures the maintenance of a practically constant 75 tension of the thread, even when the spool is being unlocked. 80

What I claim is:

1. In combination with a braiding machine spindle, a bracket secured to the 85 spindle provided with means for supporting a spool on a substantially horizontal axis and having an upwardly extending arm formed near its extremity with an eyelet, a tension lever and a locking lever mounted 90 on said bracket on substantially horizontal axes, said levers having eyelets near their extremities and being adapted to be moved by the tension of a thread passing through their eyelets and through the eyelet of said 95 arm into positions such that all of said eyelets are in substantial alignment, and biasing means for said levers adapted to move the locking lever into engagement with the spool and the tension lever away from the 100 locking lever when tension on the thread is relieved.

2. In combination with a braiding machine spindle, a bracket secured to the 105 spindle provided with means for supporting a spool, two levers mounted side by side on said bracket on substantially horizontal axes and having upwardly extending arms in the extremities of which are formed eyelets, said levers being adapted to be moved 110 so that their eyelets are in substantial alignment when tension is placed on a thread passing therethrough, one of said levers being provided with an arm adapted to be moved into locking engagement with the 115 spool when such tension is relieved and spring means acting to move the other lever with a substantially constant moment of force when the tension is relieved.

3. In combination with a braiding machine spindle, a bracket secured to the spindle provided with means for supporting a spool on a substantially horizontal axis and having an upwardly extending arm formed near its upper end with an eyelet, a tension lever and a locking lever mounted on said bracket on substantially horizontal axes, said levers having upwardly extending arms provided 125 at their extremities with eyelets and adapted to be moved by the tension of a thread 130

passing through their eyelets and through the eyelet of said arm into positions such that all of the eyelets are in substantial alignment, said tension lever being provided near its upper end with a projection adapted to engage the locking lever and hold it out of locking engagement with a spool when

the arms are in said positions, and spring means adapted to move said locking lever into locking engagement and the tension lever away from the locking lever when tension on the thread is relieved. 10

In testimony whereof I affix my signature.
GUSTAVE PERRON.
